UNITED STATES PATENT OFFICE.

ALAN ROBB FERGUSSON, OF CHICAGO, ILLINOIS.

INDEXING MACHINE.

1,205,180.

Specification of Letters Patent. Patented Nov. 21, 1916.

Application filed November 29, 1915. Serial No. 63,995.

To all whom it may concern:

Be it known that I, ALAN R. FERGUSSON, a citizen of the United States, residing at Chicago, in the county of Cook and State of Illinois, have invented a new and useful Indexing-Machine, of which the following is the specification.

This invention relates to a translating device for translating names, titles or the like which are to be classified or indexed into numbers.

In a co-pending application, Serial No. 63996, filed Nov. 29, 1915, I have disclosed a method of indexing and recording which consists in assigning to each letter of the alphabet an arbitrary number between one and nine whereby the entire alphabet will be divided into three series of such numbers; and in then translating names into said numbers entering the resulting numbers upon cards or the like and numerically arranging said cards or the like. According to such a system, every name has associated therewith a number which carries upon its face the means for properly indexing, placing or finding said numbers.

It is an object of this invention to provide a mechanical means whereby names may be instantly translated into the numbers employed in the system described, whereby the use of charts, keys, tables or their equivalents, is entirely dispensed with and it is only necessary to write the name upon the machines to reveal its corresponding number.

It is another object of the invention to provide a machine wherein the name may be written either in letters or in terms of numbers at the will of the operator.

Other objects and advantages in the invention will appear as the description to follow proceeds.

In the drawings, Figure 1 represents the key-board of a typewriter modified according to my invention. Fig. 2 is a side elevation of the key-board of one printing hammer of said typewriter.

In carrying out my invention, I preferably employ a standard typewriter modifying this machine so as to produce the results desired. In my classification system, I arbitrarily assign numbers between one and nine to each letter of the alphabet. I preferably do this by successively following the keys of a standard typewriter beginning at the upper left-hand corner of the series of

letter keys and numbering each successive key successively to the right as indicated in Fig. 1. I replace the standard letter key by keys bearing the same letters and also the corresponding numbers. Thus the "Q" key will bear a capital Q and a 1; the "G", a capital G and a 6. Thus each letter key has marked upon it the corresponding number according to my system. I provide the printing hammers of the typewriter with both letters and numbers, the numbers being lower case and the letters, upper case; so that if any name is to be translated into the number system, it will only be necessary for the operator to write the name in the ordinary fashion upon the corresponding letter keys of the typewriter in lower case, the result being the translation of the name into corresponding numbers.

In making up cards, loose-leaf ledger sheets or the like, according to my invention, it is preferable to have each card bear the name as well as the index or recording number which is the means of its location and classification. This may be accomplished upon the machine constructed according to my invention simply by writing the name again in upper case, the result being the name printed in capital letters. Thus in making out a card or loose-leaf ledger sheet for my indexing and recording system, the operator has first merely to write the name (or predetermined number of its letters) in the ordinary fashion upon the machine, the result upon the card being the name in numbers. The operator has then merely to shift to upper case to write up the name in full in the ordinary fashion, the result being the name printed in capital letters. By this means, translation into the number system is made mechanical, tables, charts, keys or the like entirely dispensed with and a mechanically obtained translation into the number system instantly obtainable by merely operating the typewriter in the usual fashion is made possible. There is no tax whatever upon the memory of the operator and the translation is made as speedy as ordinary writing.

Having now described my invention, what I claim and desire to secure by Letters Patent is:—

1. A typewriting machine having the key levers provided with the letters of the alphabet and numerals the numerals being arranged in series running up to 9, whereby a

plurality of key levers will be provided with the same numerals, and type bars being provided with letters and numerals corresponding to those on the key-board.

2. A typewriting machine having key levers provided with the letters of the alphabet, type bars operated by said key levers, series of numerals on the type bars to correspond individually to all the letters on the key levers, all of said numerals being less

than 10 whereby the operation of any alphabetic key lever will result in the printing of a numeral less than 10.

In witness whereof, I hereunto subscribe my name to this specification in the presence 15 of two witnesses.

ALAN ROBB FERGUSSON.
